UNITED STATES PATENT OFFICE.

EDMOND GAUDIOZ, OF WATFORD, ENGLAND, ASSIGNOR TO WHITCOMBE, McGEACHIN & CO., OF NEW YORK, N. Y., A PARTNERSHIP COMPOSED OF H. A. WHITCOMBE AND GEORGE McGEACHIN.

DESIGN FOR A TEXTILE FABRIC OR ARTICLE OF SIMILAR NATURE.

60,134.

Specification for Design.

Patented Jan. 3, 1922.

Application filed June 25, 1921. Serial No. 480,452. Term of patent 3½ years.

To all whom it may concern:

Be it known that I, EDMOND GAUDIOZ, a citizen of the Republic of France, residing at 33 Malden Road, Watford, Hertfordshire, England, have invented a new, original and ornamental Design for a Textile Fabric or Article of Similar Nature, of which the following is a specification, reference being had to the accompanying drawing, forming part thereof.

The figure is a plan view of a portion of a printed fabric showing an embodiment of my new design. It is to be understood, however, that my new design may be applied not only to fabrics, but also to wall paper, wrapping paper, or similar articles having surface ornamentation, without departing from what I claim as my invention.

I claim—

The ornamental design for a textile fabric or article of similar nature, substantially as shown and described.

EDMOND GAUDIOZ.
